UNITED STATES PATENT OFFICE

2,510,258

DEVICE FOR DETECTING BENT SPINDLES

John D. Rust, Memphis, Tenn.

Application August 20, 1946, Serial No. 691,782

5 Claims. (CL. 56—42)

1

My invention which relates in general to cotton picking machines, more specifically relates to devices for signalling the operator in the event any spindle or spindles become bent out of their path of movement to a degree that would interfere with the proper operation of the machine.

The primary object of this invention is to provide a mechanical device, either to give to the operator a visible signal or an audible signal or both, in the event that picking spindles become bent too much to pick effectively.

Other objects will in part be obvious and in part will be pointed out hereinafter.

To the attainment of the aforesaid objects and ends invention also resides in the novel details of construction, combinations and arrangements of parts all of which will first be fully described and then be specifically pointed out in the appended claims, reference being had to the accompanying drawing in which:

Fig. 1 is a plan view of a portion of a cotton picking machine of the Rust type, employing one embodiment of my invention, the cover plate over the fore part of the machine being omitted.

Fig. 2 is an elevation of the device looking in the directions of the arrows *a* in Fig. 1, parts being broken away.

Fig. 3 is a plan view similar to Fig. 1 of another embodiment of the invention, the cover plate over the fore part of the machine being removed.

Fig. 4 is a diagrammatic view of a further modification of my invention.

In the drawing in which like numerals of reference indicate like parts in all the figures 1 represents the frame of a Rust cotton picker, 2 the conveyor drive axle, 3 the upper drive sprocket for the slat-conveyor-chain 4, 5 represents the spindles, and C represents the cover plates which rest on the frame, all of which may be of the usual construction (see for example the covers 6^a, 7, 8, 9^a in Rust Pat. No. 2,076,598, issued April 13, 1937).

Mounted by clamps 6 on a suitable part of the frame 1 is a non-rotating rod 7 to which arms 8 and 9 are welded, as at *w*, or in any other suitable way secured to the rod. The arms 8 and 9 have bearing holes for the bearing ends 11 and 12 of a rock shaft 10.

To the shaft 10 there is welded, or otherwise suitably fixedly secured, a plurality of parallel channel iron arms 13 which are sufficiently spaced apart to provide passages 14 through which unbent spindles pass.

A sleeve 15 is secured by a set screw 16 to the bearing end 12 of the shaft 10 and has an arm

2

17 having a hole through which a bolt 19 passes. The bolt 19 also passes through a lug 18 secured on the arm 8 and carries jam nuts 20 and a spring 21, the latter serving to normally hold 5 the shaft 10 with its arms in the normal position shown in Fig. 1. When in this position the spindles (unbent ones) pass between upper and lower ones of the arms 13 as indicated in Figs. 1 and 2 by the numeral 5. When, however, a spindle is 10 bent up or down as at 5^a in Fig. 2, the bent spindle end will ride in the groove of an arm 13 and push it to the position shown in Fig. 3. This action is taken advantage of to operate a signal such as that produced by rotation of shaft 10 15 acting on a bent rod 22 (Fig. 1), the movement of which notifies the operator by visible means (the position or movement of that portion of the rod 22 which projects above the frame and cover plate) that a spindle is bent whereupon 20 he can stop the machine from further operation, or the movement of the arms 13 and shaft 10 may be utilized to operate a circuit controller 23, 24, 26, 25 (Fig. 3) controlling a circuit 27 in which is an audible signal 28 and a source of 25 electric energy B.

The rod 22 and the electrical signal device may be employed together if desired or only one of them may be used.

Further, if desired, the electrical device may be 30 adapted to stop the machine automatically by substituting a circuit breaker 23^x, 26^x for the circuit maker 23—26 and connecting it in the ignition circuit 27^x, 28^x, B^x of the tractor used to propel the machine.

35 The present application is a continuation in part of my application, Serial Number 531,632, filed April 18, 1944 now Pat. No. 2,458,531.

From the foregoing description taken in connection with the accompanying drawing forming 40 a part hereof it is thought the construction, operation and advantages of my invention will be clear to those skilled in the art.

What I claim is:

45 1. In a cotton picking machine, the combination of an endless conveyor carrying rows of cotton picking spindles, with mechanical, electrical means operated by abnormally bent spindles for audibly signalling the operator of the machine.

2. In a cotton picking machine wherein an 50 endless conveyor carries rows of cotton picking spindles, the improvement which comprises means operated by abnormally bent spindles for signalling the operator of the machine, said means comprising a rock shaft, means for supporting said shaft on the picking machine,

55

grooved arms carried by said shaft and spaced sufficiently apart to permit passage of normal spindles between said arms, said arms being positioned to project over the ends of passing spindles and receive bent spindles and be pushed away by said bent spindles, means continuously urging said arms toward the spindles and a signal operable by the rocking of said rock shaft.

3. In a cotton picking machine wherein an endless conveyor carries rows of cotton picking spindles, the improvement which comprises means operated by abnormally bent spindles for signalling the operator of the machine, said means comprising a rock shaft, means for supporting said shaft on the picking machine, grooved arms carried by said shaft and spaced sufficiently apart to permit passage of normal spindles between said arms, said arms projecting over the ends of passing spindles and positioned to receive bent spindles and be pushed away by said bent spindles, means continuously urging said arms toward the spindles, a signal circuit including a signal, a source of energy and a circuit controller, the latter being operatively connected with said rock shaft.

4. In a cotton picking machine wherein an endless conveyor carries rows of cotton picking spindles, the improvement which comprises means operated by abnormally bent spindles for signalling the operator of the machine, said means comprising a rock shaft, means for supporting said shaft on the picking machine, grooved arms carried by said shaft and spaced sufficiently apart to permit passage of normal spindles between said arms, said arms projecting over the ends of passing spindles and positioned to receive bent spindles and be pushed away by

said bent spindles, means continuously urging said arms toward the spindles, and a signal rod carried by said rock shaft.

5. In a cotton picking machine wherein an endless conveyor carries rows of cotton picking spindles, the improvement which comprises means operated by abnormally bent spindles for signalling the operator of the machine, said means comprising a rock shaft, means for supporting said shaft on the picking machine, grooved arms carried by said shaft and spaced sufficiently apart to permit passage of normal spindles between said arms, said arms projecting over the ends of passing spindles and positioned to receive bent spindles and be pushed away by said bent spindles, means continuously urging said arms toward the spindles, said continuously urging means comprising an arm on said rock shaft, a lug on said supporting means and a spring-bolt connection between said last named arm and said lug, and a signal operatively connected with said rock shaft.

JOHN D. RUST.
